(57) **CLAIM**

I claim the ornamental design for a masonry cutting tool, as shown.

DESCRIPTION

FIG. 1 is a perspective view of a masonry cutting tool showing my design;

FIG. 2 is another perspective view thereof;

FIG. 3 is a top plan view thereof;

FIG. 4 is bottom view thereof.

FIG. 5 is a front elevation view thereof; and,

FIG. 6 is a side view thereof.
